UNITED STATES PATENT OFFICE.

HIRAM W. BLAISDELL, OF LOS ANGELES, CALIFORNIA.

APPARATUS FOR HANDLING MATERIAL.

No. 910,986.

Specification of Letters Patent.

Patented Jan. 26, 1909.

Application filed September 18, 1905. Serial No. 279,043.

To all whom it may concern:

Be it known that I, HIRAM W. BLAISDELL, a citizen of the United States, residing at Los Angeles, in the county of Los Angeles and State of California, have invented certain new and useful Improvements in Apparatus for Handling Material; and I do hereby declare the following to be a full, clear, and exact description of the invention, 10 such as will enable others skilled in the art to which it appertains to make and use the same.

This invention refers to means for handling material, and has for its object to provide an apparatus whereby material can be received from an endless belt conveyer situated at the side of a row of vats or other receptacles and uniformly distributed in said vats by means of a centrifugal or other distributor. 15

20 A further object of the invention is to provide means whereby the cross conveyers may be retracted to avoid posts or other obstructions situated at the side of the vats.

25 Another object of this invention is to provide a cover for the main conveyer belt above mentioned.

30 Still another object of this invention is to provide an apparatus in which one cross conveyer may be utilized to carry material from either side of the row of vats to the center of the traveling structure and there discharged.

35 With these, and other objects in view, the invention consists of the construction herein described, and illustrated in the accompanying sheets of drawing, in which—

40 Figure 1 is a perspective view of the main construction and Fig. 2 is a similar view of an alternative construction. Fig. 3 is a detail view of the gearing in the above construction.

45 Referring to the drawings, numeral 1 designates a tank or vat; numeral 2 is a timber, supported at the side of a row of said vats on which timber is mounted a rail 3, whereon are adapted to travel wheels 4, supporting frame 5. Transverse timbers 6 rest upon the frame 5 and have tongues or guides 7, which engage grooves in the extensible frame 8. Affixed to frame 5 is a bracket 9 50 having a bearing formed therein in which a shaft 10 turns, the lower part adjacent to bracket 9 having fixed thereto a pinion 11, which meshes with a rack 12, fixed to the extensible frame 8. Above the pinion 11 is secured a ratchet 13, which may be engaged

by pawl 14, carried by bracket 9. The upper end of shaft 10 is provided with a hand wheel 15. At the outer end of frame 8 are bearings 16, wherein is journaled a shaft carrying a drum 17. Near the middle portion of timbers 6 are situated similar bearings, carrying similar drums, on the shaft of which are mounted pulleys 19, and upon the inner end of the extensible frame, and also at an intermediate point thereof, are mounted troughing idlers 20. Over drums 17 and the troughing idlers 20, a cross conveyer belt 21 is adapted to travel, the under lead thereof being supported in the usual manner by idlers 22. Adjacent and parallel to timbers 2 are supported, in any convenient manner, timbers 23, to which are affixed rails 24, on which travels a tripper 25, designed to discharge material from the main belt 26, the upper lead of said main conveyer 25 being supported in the usual manner by troughing and plain idlers respectively. A shed or cover 27, being supported on posts 28, is erected over the main conveyer for the purpose of protecting it from the weather. 30 A cover 29 supported by posts 30 is placed over cross conveyer 21. At the center portion of the length of timbers 6 is mounted a bracket 31, wherein is journaled a shaft 32 to which motion may be applied by any suitable means. The lower end of shaft 32 carries a centrifugal distributor 33. It is to be understood that in this principal construction these elements may be duplicated at the opposite end of the traveling structure 35 and that any number of vats 1, or other suitable containing means, may be used.

Referring to the alternative construction illustrated in Fig. 2 which shows a single auxiliary conveyer movable into operative relation with either of the main conveyers; upon timbers 6 are mounted rails 34, the ends of which may be upwardly deflected for the purpose of arresting the travel of the apparatus mounted thereon. On the rails 34 runs a conveyer carriage 35 supported on wheels 36 and provided with bearings at its extremities, in which turn shafts, to which are affixed drums 38 and 39, over which, and troughing idlers 20 passes the upper lead 100 of conveyer 21. Suitably supported on the carriage 35 is the motor 40 which by means of shaft 41 and gearing in case 42 communicates motion to the shaft of the drum 38. 105

On the central portion of the apparatus is 110

mounted a bracket 43, supporting shaft 44 on the upper end of which is affixed a bevel gear 45, meshing with a bevel pinion 46, on the shaft 47, on the other end of which shaft 5 is a pulley 48, which receives power from any desirable source, and transmits it through shaft 47, pinion 46, gear 45, to shaft 44, which turns the centrifugal distributor 33.

The operation of the construction shown 10 in Fig. 1 is as follows:—Material being deposited upon main conveyer belt 26, by any suitable apparatus, it is conveyed to the tripper 25, and discharged thereby onto the transverse conveyer 21, and by it, conveyed 15 and discharged upon the centrifugal distributor 33, the latter depositing the same uniformly in the vat 1. When it is desired to move the apparatus from one vat to another, the extensible frame 8 is retracted 20 through the instrumentality of the hand wheel 15 and the shaft 10, and the mechanism operated thereby, and the apparatus propelled by any suitable means to the point at which it is required to use it. The tripper 25 25 is also run along the rails on which it is supported and the extensible frame reextended, as will be readily understood by those skilled in the art to which this invention appertains.

30 Referring to the operation of the alternative construction shown in Fig. 2, the motor 40 being started, the conveyer 21 is operated by the mechanism hereinbefore described. Material is deposited upon the cross conveyer 21 by a tripper, as shown and described 35 in the main construction, or by any other suitable means, and the conveyer 21 being in motion, the material is carried by it over the drum 39, where it is discharged onto the 40 centrifugal distributor 33. When it is desired to move the traveling structure along a row of vats, and in order to avoid obstructions at the side thereof, the conveyer carriage 35 is moved along rails 34, till the end 45 thereof clears said obstructions. When it is necessary to receive material from a tripper at the other side of the traveling structure the conveyer carriage is moved along rails 34 to the other side of the centrifugal distributor, 50 the motor is reversed and the material is carried over drum 39 and discharged onto the centrifugal distributor as hereinbefore described.

Claims.

55 1. A main conveyer on fixed supports, a tripper movable along the line of the main conveyer, a traveling structure supporting an auxiliary conveyer at an angle with the main conveyer, means for extending and retract-

ing the frame of the auxiliary conveyer and 60 means for operating the parts.

2. A main conveyer and a shelter for the same, a tripper adjacent to said conveyer, a traveling structure supporting an auxiliary conveyer, means for extending the auxiliary 65 conveyer into an operative position to receive material from said tripper, means for retracting the frame of said auxiliary conveyer and means for operating the parts.

3. A main conveyer, a tripper adjacent 70 thereto, a traveling structure supporting an auxiliary conveyer at an angle with, and overlapping the main conveyer, so disposed as to receive material from said tripper, means for retracting and extending the frame 75 of the auxiliary conveyer and means for operating the parts.

4. A main conveyer, a tripper movable along the line of the main conveyer, a traveling structure supporting an auxiliary conveyer, means for retracting the frame of the auxiliary conveyer, means for extending the auxiliary conveyer into a position to receive material from said tripper, and means for 80 operating the parts.

85 5. A main conveyer, a tripper thereon, a traveling structure supporting an auxiliary conveyer, and a shelter for the same, means for retracting the frame of the auxiliary conveyer, means for extending the auxiliary conveyer so as to receive material from said tripper, means for holding the extended auxiliary conveyer in place and means for operating the parts.

90 6. A main conveyer, a movable tripper adjacent thereto, a traveling structure supporting an auxiliary conveyer at an angle to the main conveyer, a rack and pinion for extending and retracting the frame of the auxiliary conveyer and a ratchet and pawl for holding 100 the same in an extended position.

7. A main conveyer, a tripper thereon, a cross conveyer supported by a traveling structure, means for extending and retracting the frame of the cross conveyer and a distributor 105 mounted on said traveling structure adapted to receive material from said cross conveyer and means for operating the parts.

In testimony whereof, I have signed my name to this specification, in the presence of 110 two subscribing witnesses at Los Angeles, in the county of Los Angeles, State of California, this 11th day of September, A. D. 1905.

HIRAM W. BLAISDELL.
